TREATMENT OF HYDROCARBON OILS

George W. Gray, New York, N. Y., assignor, by
mesne assignments, to Texaco Development
Corporation, New York, N. Y., a corporation
of Delaware

Original application July 15, 1929, Serial No.
378,237. Continuation of application January
21, 1933, Serial No. 652,786. Divided and this
application July 7, 1936, Serial No. 89,422

1 Claim. (Cl. 196—49)

This application is a division of application Serial No. 378,237, filed July 15, 1929, which has matured into Patent 1,953,013, issued March 27, 1934, and is a continuation of application S. N. 652,786, filed January 21, 1933, and contemplates an improvement in the treatment of hydrocarbon oils in which oil is subjected to cracking, the products of cracking subjected to distillation to separate out a heavy residue and a vapor fraction, and in which the vapors are fractionated to separate out in addition to a light distillate of the character of gasoline a heavier fraction suitable for further cracking, and an intermediate fraction which is blended with the heavy residue to form a fuel oil of desired test.

In order to more fully disclose the invention reference will now be had to the accompanying drawings, wherein

Figure 1 is a diagrammatic sectional elevation 20 of an apparatus adapted for the practice of the invention.

Figure 2 is an enlarged partial section taken on the line 2—2 of Figure 1.

Figure 3 is an enlarged partial section of the 25 primary distilling chamber showing valve mechanism controlling the transfer of liquid to the secondary distilling chamber.

Figure 4 is an enlarged view of this valve in side elevation.

Figure 5 is an enlarged view in diagrammatic elevation showing a means for controlling the passage of vapor from the primary distilling chamber to its fractionating tower.

Referring now more particularly to Figure 1, 35 it will be seen that the apparatus illustrated includes a primary distilling chamber 10 in vapor communication with a fractionating tower 11 and a secondary distilling chamber 12 in vapor communication with a fractionating tower 13 and arranged to receive the partly distilled residue 40 from the primary still 10. The oil to be distilled is introduced to the still 10 by means of a charging line 14 which may have a valve 15 for regulating the admission of oil to the still 10 and also, if necessary, for reducing pressure from 45 that obtaining at the source of supply. The line 14 may communicate with one or more batteries of cracking converters or stills and is adapted for conducting tar or residue from the cracking 50 stills to the expansion and distilling chamber 10.

The charging line 14 is shown as entering the distilling tower 10 at an intermediate point therein between baffles 16 which are in the form of circular discs suitably secured to the shell of the chamber 10 and formed with concentric central

openings 17, as shown. The line 14, as clearly indicated in Figure 2, is arranged to discharge the oil tangentially into the chamber 10 so as to impart a whirling movement of the oil adjacent the baffles 16. The diameter of each of the 5 openings 17 may be the same. However, if the holes be made of different diameters it is ordinarily preferable that the upper opening 17 be of the smaller diameter since, if the upper opening be of greater diameter than the lower opening there may be a tendency to decrease the capacity for efficient separation of gas and vapors from the liquid. Underneath the baffle 16 one or more similar baffles 18 may be provided, as 10 shown in the form of a circular disc having a central opening so as to thus assist in continuing the centrifugal action initiated between the baffles 16. Above the baffles 16 a plurality of baffles 20 are disposed in staggered relation, these baffles being preferably of semi-circular shape 15 and extending preferably only to the center of the chamber so that plates mounted on opposite sides will not overlap. It may even be preferable under certain conditions to have these baffles extend less than to the center of the 20 chamber, since their primary function is to bring about a tortuous path of movement of the vapors and to knock back the liquid particles entrained therewith. This can be done quite effectively 25 without overlapping of the baffles, which would 30 tend to reduce the capacity of the chamber.

The line 21 is arranged to conduct liquid from the primary distilling chamber 10 to the secondary distilling chamber 12. As clearly shown 35 in Figures 3 and 4 the end of the line 21 in the chamber 10 is connected to a fitting 22 formed with an angular face 23 which constitutes a seat for a flapper valve 24. The fitting 22 carries lugs or bosses 25 within which is mounted a pin or shaft 26 which constitutes a pivotal support for 40 the valve 24. The shaft 26 extends outside the wall of the still 10 through a stuffing box 27 and carries a lever arm 28 provided with a weight 29 which is arranged to normally hold the valve 24 in open position. The flapper valve 24 carries 45 a paddle or element 30 disposed at an angle to it so that when the valve is open the flow of fluid entering the valve chamber 22 will come in contact with the element 30 so as to thus tend to close the valve. The extent of movement of the 50 valve 24 from the closed to the wide open position is preferably limited. Thus for example the valve seat 23 may be at any angle of approximately 60° and the valve 24 permitted to move within about a 60° arc from the closed to the 55

wide open position. It is preferable to provide the valve mechanism so that the valve will normally be either in the wide open or fully closed position and so arranged that whenever the force directed against the element 30 is sufficient to overcome the force of the weight 29 tending to hold the valve open, the valve will thereupon close with an accelerated movement. It will then stay closed until the up-stream pressure falls to within a predetermined differential in excess of the down-stream pressure. This differential is determined by the size of weight 29, the length of lever arm 28 and the effective area of seat 24.

It is sometimes desirable for flushing purposes to withdraw residue from the lower part of the chamber 10 in addition to that which is normally discharged through the line 21 and to accomplish this a slotted pipe 31 is shown extending upwardly from the bottom of the distilling chamber 10 and communicating with a drawoff line 32. By having the pipe 31 slotted it is possible to withdraw liquid from the chamber 10 at points above any coke deposits that may collect in the lower end of the chamber. It is advantageous to insert temperature indicating means at different levels in the lower portion of the chamber so as to indicate to the operator the building up of any coke deposits and the desirability of withdrawing liquid through the pipe 31. The accumulation of coke in the chamber may be indicated by a decrease in temperature at the place where the deposit may occur. Ordinarily it is preferable to make drags through the line 31 at the periods of maximum pressure in the tower 10 which normally is at approximately the end of a drag from the pressure stills through the line 14.

The vapors and gases separated in the tower 10 are withdrawn through a vapor line 33. Instead of extending directly to the fractionating tower 11 this line is shown as leading to a heat exchange element 34 for heating the steam supplied to the secondary distilling chamber 12 so as to thus enable the utilization of low temperature or exhaust steam. The vapor line 33 is shown as terminating at the upper end of the chamber 34 which is formed into an upper header by means of a plate 36. A plurality of tubular elements 35 positioned within the chamber extend from the plate 36 to a lower plate 37 which forms a header at the lower end of the chamber. The vapors pass from the upper header through the tubes 35 to the lower header. An exhaust steam line 38 admits steam to the space around the tubes above the plate 37 while an outlet line 39 is provided for the steam just below the plate 36. The steam in passing through the shell of the exchanger is heated by means of the hot vapors passing downwardly through the tubes of the exchanger and the vapors together with such condensate as is formed enter the pipe 40 by which the vapors and liquid condensate are conducted to the tower 11.

To control the passage of vapor from the distilling chamber 10 to the fractionating tower 11 and to prevent undue rises in pressure in the fractionating tower the valve mechanism shown in Figure 5 is provided. The valve actuating mechanism includes a leaf or sheet 41 pivoted at 42 and disposed within the pipe 33 in the path of the vapors. The passage of vapor through the pipe 33 tends to swing the element 41 on its pivot, it tending to approach a vertical position or position parallel with the flow of vapor at maximum pressure or vapor flow. The pin 42 extends

exteriorly of the pipe 33 and carries a weighted element 43 which tends to hold the element 41 in the horizontal position or in a position cross-wise of the flow of vapors. A lever arm 44 is also secured to the pin 42 and is in operative connection with one arm of a rocker arm 45 by means of a connecting rod 46. The other arm of the rocker arm 45 is connected by rod 47 to a lever 48 arranged to operate a butterfly valve 49 within the pipe 33. When the pressure rises in the still 10 due to increased influx of material from the line 14 the increased vaporization produces a greater pressure head on the line and increased flow through the line 33 so that the element 41 is moved toward the vertical position to thus 15 actuate the lever 44, connecting rod 46, rocker arm 45, connecting rod 47 and lever 48 to move the valve 49 toward the closed position. In other words the greater the pressure on the leaf 41 or the greater the flow of fluid through the line 33 20 the greater the tendency for the valve 49 to move to the closed position and thus retard or stop the flow of vapor. The arm carrying the weighted element 43 is preferably placed at such an angle that the restoring force tending to return the leaf 25 41 to its horizontal position increases as the leaf is forced more and more into the vertical position. As a result of this control mechanism, in spite of wide fluctuations in pressure in the distilling chamber 10, the transfer of these violent 30 fluctuations to the tower 11 is prevented. While there may be some pressure variation in the tower 11 the peak pressure loads are topped off so that it is thus possible to obtain in the tower 11 distillates of more uniform character throughout a run than could be obtained if the extreme pressure fluctuations which may take place in the chamber 10 were permitted to be transferred into the tower 11.

The vapor line 40 extends to the bottom of the 40 tower 11 which is shown formed with a plurality of sections A, B, and C, each of which sections is made up of a plurality of bubble trays 50. A trap 51 is shown for collecting condensate from the section A and a line 52 extending to a cooling coil 45 53 is provided for the removal of this cut from the fractionating tower. An outlet pipe 54 extends from the cooling coil 53 to tankage (not shown). A reflux pump is connected to the line 54 and provided with a discharge line 56 so as 50 to pump a portion or all of the condensate to the section B to serve as a reflux therefor.

In order to regulate the quantity of reflux thus returned to the section B, the line 56 will preferably be provided with a pressure-controlled valve 56¹ so arranged that it will be opened a greater or less extent, depending upon the pressure at the bottom of the section B. Thus when an increase in pressure occurs at the bottom of section B, due to a greater quantity of vapors 60 being passed to the tower by the line 40, the valve 56¹ will be opened to a greater extent to permit the introduction of a greater amount of reflux. The pressure-controlled diaphragm for operating the valve 56¹ may be of conventional construction, although it will preferably be provided with a relatively strong spring so that the extent to which the valve is opened when the pressure increases will depend upon the amount of such pressure. A trap 57 is provided for receiving condensate from the section B and an outlet line 58 extends to a cooling coil 59 for removing this fraction from the tower. An outlet line 60 extends from the cooling coil 59 to tankage (not shown). A reflux pump 61 is connected to the 70 75 80 85 90 95 98

line 60 and provided with a discharge line 62 for introducing as a reflux to the section C a portion or all of the condensate taken off from section B. A pressure-controlled valve 62¹ will preferably be provided in the line 62 and may be controlled by the pressure at the bottom of the tower 11 in a manner similar to the control of the valve 56¹. The final condensate formed in the tower is collected in the bottom and the discharge of this liquid from the tower may be controlled by means of a float 63 operatively connected to a valve 64 in an outlet line 65. The outlet line is shown extending to a cooling coil 66 provided with a discharge line 67 extending to tankage (not shown).

15 A vapor line 68 extends from the tower 11 to a reflux condenser 69 provided with a reflux condensate line 70 for conducting reflux to the upper section A of the tower 11. The reflux condenser 69 may be water-cooled or otherwise cooled, as 20 may be desired. The line 56 is shown provided with a branch line 56a so that if desired a portion of the condensate from the condenser 53 may be admitted as reflux to the upper section A. This branch line may similarly be provided with a 25 pressure-controlled valve regulated by the pressure at the bottom of section A in the same way that the valve 56¹ is controlled. A vapor line 71 is shown with a pressure regulating valve 72 extends to a condenser coil 73 provided with an outlet 30 line 74 to a receiver or accumulator drum 75. The pressure regulating valve 72 may be operated in any suitable manner. It may be operated merely by hand, although one advantageous arrangement is to operate the valve 72 by a pressure dia- 35 phragm, as shown, controlled by the downstream pressure so that when the pressure in the condenser rises, the valve moves to the closed position to thus reduce or entirely stop the delivery of liquid to the condenser 73. A line 77 is shown 40 having a valve 78 controlled by the float 79 in the drum 75. The valve 78 may be so operated by the float 79 that when the liquid level is relatively high no gas is allowed to escape through the line 77 but with decreased liquid levels gas 45 is permitted to escape. By partially closing the valve in the outlet pipe 76 the flow of gas and naphtha into the receiving drum 75 can be regulated. It should be noted here that due to the admixture of gases with the liquid hydrocarbons 50 rising through the pipe 74, the gas lift principle becomes effective to permit placing the drum 75 at a relatively high elevation with a small pressure drop through this pipe. This makes it possible to operate the system under extremely low 55 pressures in the tower 11 and drum 75 without requiring a pump to force the distillate from the drum to tankage.

If desired, distillate from the line 74 or drum 75 may be pumped to the top of the tower 11 to serve as a reflux therefor, in addition to or in lieu of the reflux supplied by the run-back line 70. A line 70a is indicated for supplying this reflux, which line may extend to a pump (not shown) that may be connected to the line 74 or drum 75. A convenient method of regulating the pumping of reflux through the line 70a to the tower 11 is to provide automatic means for controlling the rate of pumping in accordance with the pressure obtaining in the tower, just as the valves 56¹ and 62¹ are controlled. This automatic means may be arranged to function so that as the pressure increases in the tower the amount of reflux admitted will be increased.

The secondary distilling chamber 12 is shown 75 in the form of a tower provided interiorly with

a plurality of baffles 80 in the upper portion thereof and a plurality of pans or trays 81 in the lower portion thereof. The line 21, which introduces residue from the primary distilling chamber 10, is shown entering the tower 12 at an intermediate point therein so as to discharge liquid onto the pans 81 while the evolved vapors will be obstructed in their passage by the baffles 80. The line 21 may be provided with a check valve 82 so as to prevent the discharge of any fluid 10 from the still 12 back to the still 10 in case the pressure in the still 12 should ever rise above that obtaining in the still 10. The line 39 is shown entering the lower portion of the tower 12 for introducing steam which has been heated 15 in the heat exchanger 34.

The withdrawal of residue from the tower is accomplished by a line 83 having a valve 84 controlled by a float 85. The line 83 is shown as being connected to the drag line 32 of the tower 10 and as extending to a cooling coil 86, the outlet of which extends to a pump 87 for removing the residue to tankage (not shown). A vapor line 88 is provided for removing the vapors to the fractionating tower 13 and the line is shown 25 equipped with a valve 49a actuated by an element 41a for the purpose of retarding the flow of vapor as the pressure in the tower 12 or flow of vapors through the line 88 increases. The elements 41a and 49a are similar, respectively, to 30 the elements 41 and 49 shown in Figure 5 which have heretofore been described in detail. The employment of the control mechanism 41a and 49a, while advantageous, is not essential and 35 might well be eliminated.

The tower 13 is shown formed with an upper section D and a lower section E divided by a partition wall 89. The line 88 is shown entering the lower portion of the section D which contains a plurality of bubble trays 90. The condensate collected in the section D is removed by a line 91 having a valve 92 controlled by a float 93. The line 91 extends to a cooling coil 94 provided with an outlet line 95 to tankage (not shown). A vapor line 96 is provided for removing steam together 45 with any oil vapors present and directing the combined vapors into the lower portion of section E which is shown provided with rock or other suitable contact material 97. A pipe 98 serves to introduce water to the section E which water may 50 for example be water that has been removed from a condenser box employed in supplying cooling to the coil 73. A line 99 is shown constituting a vent to the atmosphere. Steam that is condensed in the section E together with such oil condensate 55 as may have been formed from any oil vapors present is collected in the bottom of the tower 13 and removed by a pipe 100 to a trap or water leg 101 in which the oil and water are separated, the oil flowing out through a line 102 and the water 60 being removed by the line 103. The line 102 is shown connected to the line 54. The reflux for the upper section D of the tower 13 is provided by a line 104 which is shown as a branch line of the reflux line 62 so that condensate from the 65 section B of tower 11 may be employed as a reflux in the tower 13. If desired other condensate such for example as condensate withdrawn from the bottom of the tower 11 may well be employed as a reflux to the section D of the tower 13. 70

The discharge line 62 of the reflux pump 61 is shown provided with a branch line 105 connected to the line 83 so that if desired distillate withdrawn from the intermediate section B of the tower 11 may be mixed with residue ob- 75

- tained from the stills 10 and 12 for the purpose of reducing the viscosity of this residue to such degree as may be desired. Instead of utilizing the condensate from the section B of tower 11 5 for mixing with the still residue any of the other condensates formed in the process may well be employed, such for example as the heavy condensate withdrawn from the bottom of section D of tower 13.
- 10 In practicing the invention with the apparatus illustrated liquid oil which has been subjected to a cracking reaction for the conversion of higher boiling hydrocarbons into lower boiling ones, either with or without accompanying distillation, 15 may be admitted through the line 14 to the primary distilling tower 10. Thus the synthetic product obtained by converting the oil in a vessel from which the vapors are not removed, or the residue resulting from carrying 20 on the cracking with concomitant distillation in a pressure still, is passed through the pressure reducing valve 15 to be thus discharged into the expansion chamber 10 under reduced pressure. The pressure is reduced to such an extent as is 25 necessary to effect the distillation of the fractions it is desired to remove from the liquid oil or residue. Thus, ordinarily when the conversion is carried on under several hundred pounds pressure, the expansion chamber 10 will be held 30 at a pressure considerably reduced from that obtaining in the converters, such for example as pressures approximating atmospheric, and depending upon the exact conditions of delivering the liquid oil or residue from the cracking chambers 35 the pressure in the expansion chamber 10 may ordinarily vary for example from approximately atmospheric pressure to 75 or 100 pounds pressure. It is desirable to reduce so far as practicable the pressure obtaining in the expansion chamber but it may be that while pressures approximating atmospheric such as 5 to 10 40 pounds may be maintained at times, that at other times during periods of heavy drags from the pressure stills the pressure may rise to the 45 upper limits mentioned.
- The liquid oil is discharged into the chamber 10 in a stream tangential to the wall of the chamber, as has been pointed out, so as to impart a whirling motion to the liquid between the 50 concentric central hole baffles 16 thus facilitating the separation of the gas and vapors from the liquid residue. By discharging the oil tangentially into the chamber at a rapid rate a centrifugal force of sufficient magnitude to materially increase the separating effect over that 55 which would otherwise take place may be accomplished. As an indication of the separating force which has been obtained in the practice of the invention it may be mentioned that in 60 some operations carried on in accordance with the invention a separating force calculated as upwards of 770 times the force of gravity has been employed. In addition to the separating action carried on in the whirling mass of oil 65 between the central hole baffles there is a further separation in the upper portion of the chamber 10. Thus the separating action that takes place in the still 10 may be referred to as a two-stage operation, the first of which is 70 carried on at relatively high speed in which separation of the vapors from liquid takes place under the influence of centrifugal action and the second stage of which takes place in the upper part of the still 10 where the vapors travel at 75 reduced velocity through the baffled portion of

the chamber wherein any solid particles of suspended coke or carbon or heavy entrained liquids are separated out from the vapors by reason of the obstructing baffles and reduced velocity.

The vapors pass from still 10 through the vapor line 33 to the exchanger 34 and thence through the line 40 to the fractionating tower 11 wherein fractionation of the vapors takes place. Liquid residue is discharged into the 10 secondary distilling chamber 12 into which steam which has been heated by heat exchange with the hot vapors from the expansion chamber 10 is introduced. The delivery of liquid or residue from the primary still 10 to the secondary still 15 12 is retarded, as has heretofore been explained, by the operation of the valve 24 in the line 21 so that undue rises in pressure in the primary still 10 or a heavy influx of material through the line into the still 10 will not overload the 20 secondary still 12 or cause the pressure to rise therein unduly. The delivery of vapors from the primary still 10 to its fractionating tower 11 is also retarded by the operation of the valve 49 in the line 33, as has heretofore been explained, so as to reduce the effect in the tower 11 of periods of high pressure or of increased evolution of vapor in the still 10.

In the fractionating equipment shown an overhead vapor fraction and three condensate cuts 30 may be taken off the fractionating tower 11. Thus a gasoline or naphtha fraction may be taken off through the line 68, passed through the reflux condenser 69 and line 71 to the condenser coil 73, the distillate being collected in the receiver 75. Fractions constituting kerosene or light or intermediate gas oil fractions may be removed from the tower through the lines 52 and 58. These cuts may be sent to separate storage or, if desired, a portion or all of these 40 fractions may be employed in refluxing towers 11 and 13, as has heretofore been explained. A heavier gas oil fraction may be withdrawn from the tower 11 through the line 65. The tower 13 in which are treated the vapors from the secondary still 12 is preferably operated so that a heavy gas oil fraction may be drawn off from the bottom of the section D through the line 91. It is preferable to maintain such temperatures in the section D that the steam which comes 45 off from the still 12 together with the oil vapors through the line 88 will not be condensed and thus the steam together with the hydrocarbon constituents that remain in the vapor form under the temperatures obtaining in the section 50 D pass out through the line 96 to the lower section E of the tower 13. Water is admitted to the contact material 97 to effect condensation of both the steam and the hydrocarbon vapors, the condensate being delivered through the line 60 100 to the water leg 101 in which separation of the oil and water takes place.

The distillation system described herein may be employed in distilling liquid oil or residue obtained from a single converter or battery of converters or it may be operated in conjunction with a plurality of converters or batteries thereof. By connecting the line 14 to a plurality of converters or batteries of converters and by properly timing the intervals between the taking of shots or drags 70 it is possible to reduce to a greater or less extent, depending upon the number of batteries thus connected, the fluctuations in pressure and in volume of liquid obtaining in the primary still 10. But the invention described herein is well adapted for 75

operation under conditions wherein extremely wide fluctuations in pressure and in volume of liquid delivered to the primary still may take place. In some cases instead of taking shots or drags from the converters the removal of liquid or residue may be made in a substantially continuous manner and in this type of operation the invention is of advantage since a continuous stream of liquid may be discharged tangentially 10 into the chamber 10 between the concentric central hole baffles 16 and the separation of vapors and gases from liquid residue carried on in an effective manner.

The gas oil cuts or fractions that are removed 15 from the fractionating towers 11 and 13 may advantageously be returned to the cracking stills or converters for further treatment. It is advantageous to return these reflux condensates to the converters in a heated condition and when it 20 is desired to operate in this manner the cooling coils employed in cooling these condensates may be omitted or the coils may be employed only for cooling such portions of the condensates as it is desired to return to the towers to serve as reflux 25 media therefor, the other portions of the condensates being conducted directly to a cracking zone for further treatment for the production of gasoline.

In order to obtain the maximum production of 30 gas oil (often referred to as cycle gas oil) adapted for returning to the cracking zone for retreatment it is desirable to carry on the distillation of the pressure tar to such an extent that the resultant residue may have a higher viscosity or a 35 lower A. P. I. gravity than may be required for a marketable fuel oil. In such case the heavy residue may be cut with a portion of the gas oil obtained from the distillation. One of the methods of operation contemplated by the invention 40 consists in utilizing the heavier gas oil obtained for return to the cracking zone and employing a lighter or intermediate gas oil fraction for admixing with the heavy residue to thereby obtain a fuel oil that will meet the specifications desired. 45 This method of operation has the advantage that the lighter or more refractory gas oil fractions which are difficult to crack are not returned to the cracking zone but are utilized in the preparation of the desired fuel oil while the heavier and less refractory gas oil fractions are employed in further cracking for the production of gasoline.

When using steam in distilling the pressure tar either in a single distilling chamber or when carrying on the distillation in two stages, such as 50 has been described as applicable to stills 10 and 12 with the introduction of steam into the secondary distilling chamber 12, it has been found that when it is desired to obtain a residue to be used for fuel purposes it is satisfactory to use comparatively low temperature steam and when 55 it is desired to obtain an asphalt best results are obtained by employing higher temperature steam.

In one method of operation contemplated by the invention oil which it is desired to distill or strip is heated to the desired distilling temperature in a tubular heater and then discharged into the still 10 tangentially of the chamber between the concentric central hole baffles 16 to thus accomplish an effective separation of the vapors from the liquid residue. This method of operation 60 may be applied to a cracking process. Thus the oil to be converted may be raised to a crack-

ing temperature in a coil or tubular heater under high superatmospheric pressure and cracked to the extent desired and then discharged into the still 10 which may be held at high superatmospheric pressure or at a pressure materially reduced from that obtaining in the coil. Separation of the vapors from the liquid is facilitated by discharging the oil from the coil into the still 10 tangentially and between the central hole baffles 16.

In describing herein the method of employing the still 10 no reference has been made to the application of heat to the still 10 other than that contained in the oil discharged thereinto for distillation because the operation carried on in this type of still is particularly adapted for carrying on distillation of oil which is received from a heated source, such as for example a coil or tubular heater or a heated body of oil from a cracking still, wherein the oil contains sufficient heat 20 for effecting the desired vaporization when discharged into the still 10. However, it is to be understood that the application of heat to the still 10, or the use of a carrier gas, such as steam, is not precluded in the practice of the invention. 25 However, one of the specific methods of operation contemplated by our invention consists in carrying on a distillation in a two-stage operation, such as has been described as obtaining in the stills 10 and 12 in which no heat need be applied to the still 10, the distillation being carried on therein by means of the heat contained in the oil discharged thereinto, and by the application of either heat or a carrier gas in the secondary 30 distilling operation carried on in the still 12. 35

Although the preferred embodiment of the invention has been set forth in connection with apparatus having a particular construction and arrangement of parts and mode of operation, it is obvious that various changes and modifications 40 may be made therein, while securing to a greater or less extent some or all of the benefits of the invention, without departing from the spirit and scope thereof. Therefore, only such limitations should be imposed as are indicated in the appended claim. 45

I claim:

In the treatment of hydrocarbon oils, the process that comprises passing residual products withdrawn from a pressure cracking still into a flashing zone wherein the residual products are subjected to flash vaporization to produce heavy residue, subjecting resultant separated vapors to fractionation in a separate fractionating zone to form a gasoline fraction and higher boiling condensates comprising light gas oil and heavy gas oil condensates, subjecting heavy residue from said flashing zone to further distillation in a secondary flashing zone to form a heavy residue having a viscosity greater than that adapted for fuel oil and produce additional heavy gas oil condensate, subjecting said heavy gas oil condensates to cracking, withdrawing said heavy residue from the secondary flashing zone and conducting it to a blending zone, blending said heavy residue therein with light gas oil condensate withdrawn from said fractionating zone, under conditions in which substantially none of the blend is vaporized and in which the light gas oil condensate is retained in the blend, to form a blended fuel oil 55 product of desired test. 60

GEORGE W. GRAY.
